United States Patent

Des. 237,462
Patented Nov. 4, 1975

237,462

BOTTLE

Bernd Peters, Jesteburg, Germany, assignor to Colgate-Palmolive Company, New York, N.Y.

Filed Mar. 8, 1973, Ser. No. 339,032

Claims priority, application Great Britain Sept. 14, 1972

Term of patent 14 years

Int. Cl. D9—01

U.S. Cl. D9—149

FIG. 1 is an elevational view of a bottle showing my new design, the opposite side being substantially the same in appearance as the side shown;

FIG. 2 is an elevational view looking from the right of FIG. 1, the opposite side being substantially the same in appearance as the side shown; and

FIG. 3 is a top plan view thereof.

I claim:

The ornamental design for a bottle, as shown and described.
